UNITED STATES PATENT OFFICE.

FREDERICK R. PETERSON, OF SPOKANE, WASHINGTON.

KEY-RING HOLDER.

Application filed August 11, 1923. Serial No. 656,872.

To all whom it may concern:

Be it known that I, FREDERICK R. PETERSON, a citizen of the United States, residing at Spokane, in the county of Spokane and State of Washington, have invented certain new and useful Improvements in Key-Ring Holders, of which the following is a specification.

This invention relates to improvements in 10 key ring holder by means of the use of which a key ring may be readily and securely attached to a belt to permit ready access thereto and to render the key ring readily detachable from the belt when desired.

15 A further object of the invention is to provide an improved holder of this character so constructed that when in position upon a belt, the latter will be threaded through the holder so that the holder may 20 be readily slipped upon the belt to the desired position convenient to the user.

25 A further object is to provide an improved holder of this character of the pivoted jaw type, the end of one of the jaws being shaped with respect to the other jaw so that when the holder is engaged over the edge of a pocket or clamped upon a garment, a portion of the pocket or garment will be wedged between the jaws, thereby 30 securely maintaining the holder against slipping or disengagement from the pocket or garment.

35 A further object is to provide an improved device of this character, which will be simple, durable, cheap, light and compact in construction and effective and efficient in operation.

40 To the attainment of these ends and the accomplishment of other new and useful objects as will appear, the invention consists 45 in the features of novelty in substantially the construction, combination and arrangement of the several parts hereinafter more fully described and claimed and shown in the accompanying drawing illustrating this invention and in which—

50 Figure 1 is a perspective view of a holder of this character constructed in accordance with the principles of this invention and showing the same applied to a belt.

Figure 2 is a view similar to Figure 1, showing the holder secured over the edge of a pocket.

55 Figure 3 is a side elevation of Figure 4, showing the holder secured to a garment.

Figure 4 is a side elevation of Figure 3.

Figure 5 is an end view of the jaws.

Referring more particularly to the drawing, the numerals 10 and 11 designate jaws which are pivotally connected together intermediate their ends as at 12, the pivot being preferably located adjacent one end of the jaws. These jaws may be of any desired size and configuration and are constructed of any suitable material but are preferably 60 constructed of metal and are so shaped that the edges thereof will be of a rounding configuration so that the jaws will not injure the garment. The extremities 13 and 14 of the respective jaws 10 and 11 are preferably 65 of a rounding configuration and slightly offset as shown in Figure 3 to form projections adapted to be gripped by the fingers to move the jaws about their pivot 12 and which portions 13—14 will prevent the fingers from slipping from the ends of the 70 jaws.

A spring 15 is coiled about the pivot 12 and tends normally to move the jaws 10 and 11 about their pivots so as to separate 80 the extremities 13 and 14 of the jaws and to move the opposite ends of the jaws into co-operative relation.

The jaw 10 is provided at its other end with an eye or loop 16 formed in any suitable manner but preferably by bending the free end of the jaw back upon itself and into shape to form a loop. The extremity 17 of the jaw 11 is deflected laterally towards the jaw 10 and is preferably shaped 90 to form teeth 18. The jaw 11 is preferably of a length slightly shorter than the jaw 10 so that the teeth 18 on the extremity 17 of the jaw 11 will contact with the jaw 10 at a point spaced from the end of the jaw, 95 preferably so as to engage the side of the loop 16, for a purpose to be hereinafter set forth.

If desired the face of the loop 16 may be provided with recesses or indentations 19 100 adapted to receive the teeth 18 of the extremity 17 of the jaw 11. These recesses or indentations 19 may be formed in any desired or suitable manner and may be of any desired configuration to conform to or receive the teeth 18.

Threaded through the loop or eye 17 on the jaw 10 is a key ring 20.

In use the holder may be placed upon a belt 21 in such a manner that the jaw 11 110 may be disposed on either side of the belt 21 as desired. That is to say the jaw 11 may

be on the outside or the inside of the belt and when in position the pivot 12 will rest upon the upper edge of the belt so as to suspend the holder and ring. The jaws 10 and 11 are of such a length that the extremity 17 will pass beneath the lower edge of the belt 21 to engage the side of the eye or loop 16 and the spring 15 tends normally to hold the extremity 17 of the jaw 11 in engagement with a portion of the jaw 10.

With this construction it will be manifest that the belt 21 will be threaded loosely between the jaws 10 and 11 and by the engagement of the edge of the extremity 17 with a portion of the jaw 10 it will be manifest that the jaws will be prevented from clamping the belt. This will enable the user to slip the holder upon the belt to any desired and convenient position. The holder may be readily detached from the belt by pressing together the extremities 13 and 14 of the jaws, and the offset portions 13 and 14 serve as a means for preventing the fingers from slipping from the ends of the jaws, when it is desired to detach the holder from the belt.

When the holder is secured over the edge of a pocket 22 or a portion of a garment 23, a portion of the garment will be wedged between the wall of the eye or loop 16 and the extremities 17 of the jaw 11, as shown more clearly in Figure 3, thereby offsetting a portion of the garment 23 which will serve to prevent the clip from becoming accidentally disengaged from the garment so that when it is desired to detach the holder from the garment it will be necessary to press the opposite edges of the jaws together against the stress of the spring 15.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A holder for key rings and the like embodying jaw like members pivotally connected adjacent but spaced from one end, an eye disposed at the other end of one of the jaws, the adjacent end of the other jaw being laterally deflected towards said eye and adapted to engage the wall of the eye, and a spring tending normally to cause the said deflected end of the jaw to engage the wall of the said eye.

2. A holder for key rings and the like embodying jaw like members pivotally connected adjacent but spaced from one end, an eye disposed at the other end of one of the jaws, the adjacent end of the other jaw being laterally deflected towards said eye and adapted to engage the wall of the eye, a

spring tending normally to cause the said deflected end of the jaw to engage the wall of the said eye, and a key ring freely suspended by said eye.

3. A holder for key rings and the like embodying jaw like members pivotally connected adjacent but spaced from one end, an eye disposed at the other end of one of the jaws, the adjacent end of the other jaw being laterally deflected towards said eye and adapted to engage the wall of the eye, a spring tending normally to cause the said deflected end of the jaw to engage the wall of the said eye, and teeth on the extremity of the said deflected portion, there being recesses in the wall of the eye to receive said teeth.

4. A holder for key rings and the like embodying jaw like members pivotally connected adjacent but spaced from one end, an eye disposed at the other end of one of the jaws, the adjacent end of the other jaw being laterally deflected towards said eye and adapted to engage the wall of the eye, and a spring tending normally to cause the said deflected end of the jaw to engage the wall of the said eye, the end of the said deflected portion and the adjacent portion of the wall of the said eye being undulated.

5. A holder for key rings and the like embodying two members pivotally connected adjacent but spaced from one end of the members, a spring tending normally to move the other ends of the members towards each other, the last recited end of one of the members being bent upon itself to form an eye the axis of which is substantially parallel with the pivot of the members, the end of the other member adjacent said eye being deflected laterally to engage the wall of the eye, and a key ring threaded through the eye.

6. A holder for key rings and the like embodying two members pivotally connected adjacent but spaced from one end of the members, a spring tending normally to move the other ends of the members towards each other, the last recited end of one of the members being bent upon itself to form an eye the axis of which is substantially parallel with the pivot of the members, the end of the other member adjacent said eye being deflected laterally to engage the wall of the eye on one side of the diametric center of the eye, and a key ring threaded through the eye.

7. A holder for key rings and the like embodying two members pivotally connected adjacent but spaced from one end of the members, a spring tending normally to move the other ends of the members towards each other, the last recited end of one of the members being bent upon itself to form an eye the axis of which is substantially parallel with the pivot of the members, the end

of the other member adjacent said eye being deflected laterally to engage the wall of the eye, teeth on the end of the said deflected portion, there being depressions in the adjacent portion of the wall of the eye to receive said teeth, and a key ring threaded through the eye.

8. A holder for key rings and the like embodying two members pivotally connected adjacent but spaced from one end, means tending normally to move the other ends of the members towards each other, an eye

formed on the last recited end of one of the members, the adjacent end of the other member being deflected towards the eye to engage the wall of the latter at a point to one side of the center of the eye to deflect over the eye the fabric clamped by the holder, and a key ring loosely suspended by the eye.

In testimony whereof I have signed my name to this specification, on this 2nd day of August A. D. 1923.

FREDERICK R. PETERSON.
